UNITED STATES PATENT OFFICE

135,528

DESIGN FOR A SWITCH ENCLOSURE

John F. Meyer, Chicago, Ill., assignor to The Exhibit Supply Company, Chicago, Ill., a corporation of Illinois

Application February 19, 1943, Serial No. 109,584

Term of patent 7 years

To all whom it may concern:

Be it known that I, John F. Meyer, a citizen of the United States, and a resident of Chicago, in the county of Cook and State of Illinois, have invented a new, original, and ornamental Design for a Switch Enclosure, of which the following is a specification, reference being had to the accompanying drawing, forming a part thereof, and in which:

Fig. 1 is a perspective view of a switch enclosure showing my new design;

Fig. 2 is a front elevational view of the same; and

Fig. 3 is a rear elevational view of the same.

I claim:

The ornamental design for a switch enclosure, as shown.

JOHN F. MEYER.
